Primary Examiner — Sandra S Snapp*Assistant Examiner* — Katherine Glennon(74) *Attorney, Agent, or Firm* — Henry M. Feiereisen LLC(57) **CLAIM**

The ornamental design for a computer for industrial purposes, as shown and described.

DESCRIPTION

FIG. 1 is a front elevation view of a computer for industrial purposes, showing our new design;

FIG. 2 is a rear elevation view thereof;

FIG. 3 is a top plan view thereof;

FIG. 4 is a bottom plan view thereof;

FIG. 5 is a right side elevation view thereof;

FIG. 6 is a left side elevation view thereof; and,

FIG. 7 is a front, top and right side perspective view thereof.

The broken line portion of the figure drawings is included to show unclaimed subject matter only and forms no part of the claimed design.

1 Claim, 7 Drawing Sheets(56)
